DESIGN FOR A CABINET FOR RADIO
PHONOGRAPH COMBINATIONS

Leonard Trank, Los Angeles, Calif.

Application May 10, 1947, Serial No. 138,966

Term of patent 3½ years

(Cl. D56—4)

To all whom it may concern:

Be it known that I, Leonard Trank, a citizen of the United States, residing at Los Angeles, in the county of Los Angeles and State of California, have invented a new, original, and ornamental Design for a Cabinet for Radio Phonograph Combinations, of which the following is a specification, reference being had to the accompanying drawing, forming part thereof.

In the drawing:

Fig. 1 is a perspective view of the radio phonograph combination cabinet, showing my new design;

Fig. 2 is a front elevation of the cabinet showing the lid in raised position;

Fig. 3 is a side elevation, and

Fig. 4 is a rear elevation.

I claim:

The ornamental design for a cabinet for radio phonograph combinations, as shown.

LEONARD TRANK.
